INVENTOR—
F. DENIZET,
BY Knab & Co. 1919.

UNITED STATES PATENT OFFICE.

FELIX DENIZET, OF PERRYVILLE, MISSOURI.

PNEUMATIC WATER-ELEVATOR.

1,295,446.

Specification of Letters Patent. Patented Feb. 25, 1919.

Application filed June 8, 1917. Serial No. 173,531.

To all whom it may concern:

Be it known that I, FELIX DENIZET, a citizen of the United States of America, a resident of Perryville, in the county of Perry, State of Missouri, have invented 5 certain new and useful Improvements in Pneumatic Water-Elevators, of which the following is a full, clear, and exact description, reference being had to the accompanying drawings, forming a part of this specification.

My invention relates to an apparatus for raising water by air pressure from wells or other basins and conducting it to any point 15 to which it may be desired to make delivery. The invention has for its object the production of a simple apparatus of this kind which is automatic in operation, and which is of such simplicity as to be not liable 20 to become inoperative or impaired by long continued use.

Figure I is a vertical section, partly in elevation, of my water elevator.

Fig. II is an enlarged side elevation of the 25 mechanism for controlling the vertical movement of the submerged tank of my water elevator.

Fig. III is an elevation of the parts shown 30 in Fig. II viewed from a point at a right angle to the point from which the parts in Fig. II are seen.

Fig. IV is an enlarged section on line 35 IV—IV, Fig. III, through the controlling valve of the elevator.

In the accompanying drawings, 1 designates an upper horizontal anchor beam or stay which serves to position a frame comprising vertical rods 2. The rods 2 extend to the bottom of the well or basin B from 40 which water is to be elevated and have fitted to them at their lower ends a bottom stay bar 3 provided with a vertical guide 4.

5 designates a tank submerged in the water in the well or basin B adapted to partly 45 take of limited upward and downward movements to provide for the actuation of certain controlling elements, as will herein-after appear. The tank 5 is in part directed during its vertical movement and held from 50 turning by a non-circular stem 6 at the bottom of the tank fitted to the guide 4. A horizontal stop bar 5' secured to the vertical rods 2, and further held from upward movement by stay rods 5^a connecting said 55 cross bar to the bottom stay bar 3, serves to limit the upward movement of the tank 5.

The tank 5 is provided with a water inlet 7, controlled by a valve 8 which opens automatically when the pressure in the basin B is in excess of the pressure in the tank 5, but 60 is held closed by pressure in the tank 5 when the pressure in the tank is in excess of that in the basin.

9 designates a vertical section of pipe fixed to the tank 5, said pipe section being disposed partly within and partly above said tank. The pipe section is telescopically fitted to a vertical water discharge pipe 10.

11 designates a U-shaped hanger depending from a horizontal supporting bar 11' 70 secured to the rods 2. A shaft 12 is journaled in the legs of the hanger 11 and has fixed to it a pinion 13, in mesh with a rack 14 secured to the pipe section 9.

A 3-way valve C located at the lower end 75 of the hanger 11 comprises a housing 15 secured to said hanger and a ported plug 16 in said housing, which is fixed to the shaft 12 and is rotatable therewith. The 3-way valve C serves to control the delivery of air 80 under pressure from a conducting pipe 17 to the interior of the tank 5, and the escape of air from said tank, as will hereinafter appear.

The air under pressure may be delivered 85 from an air compressor or other suitable source of supply through the conducting pipe 17 leading to the housing of the 3-way valve C, and when the plug of said valve is in the position in which it is seen in Fig. IV, the air 90 in the pipe 17 will pass to a pipe 18 leading to the interior of the water delivery pipe 10, said water delivery pipe preferably including a union 19 through which the pipe 18 enters the pipe 10. The pipe 18 extends 95 downwardly in the water delivery pipe 10 to the lower end of the latter, and preferably leads to the exterior of said pipe within the tank 5 and then upwardly in said tank to a point near the top of the tank, as seen in Fig. 100 I, so that the air passing through the pipe 18 may be discharged above the level of water in the tank 5.

The housing of the 3-way valve C is provided with a duct 15', which is open to the 105 atmosphere and which is adapted to be placed in registration with the pipe 18 when the valve plug 16 is adjusted to permit such registration, thereby providing for the venting of air through the pipe 18 from the interior of the tank 5 at a time to be herein mentioned.

- 20 designates a trip arm fixed to the shaft 12 by which the 3-way valve C is operated. This trip arm is preferably in the form of a sector and is located at the end of said 5 shaft opposite to that at which the 3-way valve C is located. At one side of the trip arm is a trip pin 21, which is movable in an arc of a circle and is adapted to be shifted with the trip arm from one side of a vertical 10 line drawn through the axis of the shaft 12 to the other side of said vertical line.
- 22 designates a rockable controller pivoted intermediate of its ends at 23 to the hanger 11, said controller comprising an 15 upper arm provided with a counterbalance weight 22' and a lower arm bifurcated to produce divergent legs 24 and 25, each of which is adapted to be engaged by the trip pin 21 on the trip arm 20.
- 20 26 designates a detent device pivoted to the hanger 11 at 23, said device being provided with a pair of spaced pendent arms 27 adapted to engage the trip arm 20, when 25 said arm is in either of its extreme positions.
- At the upper end of the detent device 26 are arms 28 provided with abutments 29 and 30 between which the upper arm of the rockable controller 22 is operable, and which are 30 adapted to be engaged by said upper controller arm when it is rocked to and fro on its point of pivotal support.
- The hanger 11 is preferably formed with an elbow 11" located at its lower end, which extends transversely of and straddles the 35 pipe section 9. This elbow serves as a support for a roller 11a located opposite the pinion 13, between which and said pinion the pipe section 9 is directed in its vertical movements.
- 40 In the practical use of my automatic water elevator the operation is as follows: When the tank 5 is supplied with water to be withdrawn therefrom through the discharge pipe 10, said tank is submerged, as 45 seen in Fig. I, and the inlet valve 8 occupies a closed position. At this time the plug 16 of the valve C is in the position in which it is seen in Fig. IV, so that there is communication between the air pipes 17 and 18 50 and air under pressure may therefore be delivered to the interior of the tank 5 to exert pressure against the water in said tank and force it through the delivery pipe 10 to the point at which it is desired to deliver the 55 water. While water is being discharged from the tank through the discharge pipe, the valve plug 16 is maintained in the position in which it is seen in Fig. IV, due to the holding influence of the detent device 60 26, the arm 27 of which abuts against the trip arm 20 and is held thereto by the weighted controller 22 lying in engagement with the abutment 30 of the detent device 26. The weighted upper arm of the 65 controller 22 constitutes a counterbalance

against the tendency of the tank 5 to float in the water in the basin B when the tank has become partially emptied by removal of water therefrom through the discharge pipe 10, and all of the parts of my water elevator 70 will retain the positions shown in Figs. I, III and IV, and in full lines Fig. II, until the tank has become sufficiently emptied to commence to rise in the basin B, due to its buoyancy. Upon the tank having been 75 emptied to the degree just referred to, it rises and carries with it the pipe section 9 and the rack 14 thereon. As a consequence of the upward movement of the pipe section 9, the rack 14 operates to rotate the pinion 13 and the shaft 12 to which the latter is fixed, whereby the valve plug 16 is turned to close communication between the air conducting pipes 17 and 18 and establish communication between the pipe 18 and the vent 80 duct 15' of the valve housing 15, so that air may be vented from the tank 5 to the atmosphere.

During the rotation of the shaft 12 to change the position of the valve plug 16 of 90 the valve C, the trip arm 20 rotates with said shaft toward the right hand relative to the position in which it is seen in Fig. I, and in full lines Fig. II, and the trip pin 21 carried by said arm strikes the leg 25 of the 95 controller 22 while said trip arm is moving to the dotted line position, Fig. II, and in consequence of this movement the controller 22 is shifted to the dotted line position, Fig. II, and shifts the detent device 26 to the 100 dotted line position, so that the valve plug 16 may be completely shifted from the position shown in Fig. IV, and the tank 5 may rise to the limit of its intended upward movement. In shifting to the dotted line 105 position shown in Fig. II, the controller 22 strikes the abutment 29 of the detent device 26 and causes the leg 27 of said detent device to engage the lefthand edge of the trip arm 20, thereby providing for the temporary detention of said trip arm and the valve plug 16 in the positions to which they have been 110 adjusted.

It will be readily understood that when the parts are in the positions last recited 115 the tank 5 is in an elevated position, and inasmuch as the compressed air pressure in the tank has been relieved there is opportunity for the pressure of the water in the basin B to open the inlet valve 8, which 120 therefore opens and water is admitted to the tank to fill it. As the tank becomes filled it settles in the water in the basin until it reaches the limit of its downward movement, and there is resultant readjustment of the shaft 12, valve plug 16, trip arm 20 and parts operable by said trip arm 125 to their original positions. As will be apparent, when the trip arm returns to its original position the stud 21 strikes the leg 130

24 of the controller 22, and said controller is tilted from the dotted line position, Fig. II, to the full line position, Fig. II, with the result of causing the detent device 26 to again engage the trip arm 20 and hold it from movement until the tank 5 again moves upwardly by flotation. An important feature of my water elevator is the connection of the air conducting pipe 18 to the water delivery pipe 10, and the support of the air pipes 17 and 18 and the air controlling valve C, so that these parts will remain stationary when the tank 5 and other moving parts partake of movement. Such arrangement avoids the use of flexible pipes such as rubber tubing, which has heretofore been used in water elevators of the type to which my invention belongs, and which become unserviceable after a short time.

20 I claim:

1. A water elevator comprising a vertically movable submerged tank, a pipe section carried by said tank, a vertical water delivery pipe to which said pipe section is slidably fitted, an air conducting pipe leading to the interior of said tank for the delivery of air under pressure thereinto, a valve in said air conducting pipe, a valve operating shaft operable by said pipe section in response to vertical movement of the latter, and means for controlling the rotation of said shaft when said tank is in a lowered position to prevent the rise of the tank until it has been emptied to a predetermined degree.

2. A water elevator comprising a vertically movable submerged tank, a pipe section carried by said tank, a vertical water delivery pipe to which said pipe section is slidably fitted, an air conducting pipe leading to the interior of said tank for the delivery of air under pressure thereinto, a valve in said air conducting pipe, a valve operating shaft operable by said pipe section in response to vertical movement of the latter, and means for holding said shaft from rotation when said tank is in an elevated position and pending the entrance of a predetermined quantity of water into said tank.

3. A water elevator comprising a vertically movable submerged tank, a pipe for conducting air under pressure to the interior of said tank, a valve for controlling passage of air through said air conducting pipe, a shaft operable in response to vertical movement of said tank whereby said valve is operated, a detent device for holding said shaft from rotation when said tank is in its extreme position in either direction of movement, and means operable in response to vertical movement of said tank whereby said

detent device is shifted to permit free rotation of said shaft.

4. A water elevator comprising a vertically movable submerged tank, a pipe for 65 conducting air under pressure to the interior of said tank, a valve in said air conducting pipe, a valve operating shaft operable in response to vertical movement of said tank, a trip member associated with said shaft, a 70 detent device for engagement with said trip member, and a controller governing the movement of said detent device pending vertical movement of said tank.

5. A water elevator comprising a vertically movable submerged tank, a pipe for 75 conducting air under pressure to the interior of said tank, a valve in said air conducting pipe, a valve operating shaft operable in response to vertical movement of said tank, 80 a trip member associated with said shaft, a detent device for engagement with said trip member, and a controller governing the movement of said detent device pending vertical movement of said tank, said detent 85 device being adapted to restrain said trip member from movement when said tank is in either elevated or lowered position.

6. A water elevator comprising a vertically movable submerged tank, a pipe for 90 conducting air under pressure to the interior of said tank, a valve in said pipe, a valve operating shaft operable in response to vertical movement of said tank, a trip member 95 associated with said shaft, a rockable detent device for engagement with said trip member, and a weighted rockable controller for holding said detent device in engagement with said trip member pending vertical movement of said tank.

7. A water elevator comprising a vertically movable submerged tank, a pipe for conducting air under pressure to the interior of said tank, a valve in said pipe, a shaft operable in response to vertical movement of 105 said tank whereby said valve is operated, a trip arm fixed to said shaft, a rockable detent device having a pair of legs, one of which is adapted to engage a portion of said trip arm when said valve is in position to 110 permit the passage of air under pressure to said tank, and the other of which legs is adapted to engage another portion of said trip arm when said valve is in position to vent air from said tank, and a controller 115 having a pair of legs operable by said trip arm whereby said detent device is shifted in response to vertical movement of said tank.

In testimony that I claim the foregoing I hereunto affix my signature.

FELIX DENIZET.
